IN-LINE CHECK VALVE

William V. Porter, % The Porter Company, 1620 S.
Seguin Ave., New Braunfels, Tex. 78130

Filed Mar. 21, 1975, Ser. No. 560,578

Term of patent 14 years

Int. Cl. D23—01

U.S. Cl. D23—22

FIG. 1

FIG. 6

FIG. 2

FIG. 5

FIG. 3

FIG. 4

FIG. 1 is a top plan view of an in-line check valve showing my new design;

FIG. 2 is a side elevational view thereof;

FIG. 3 is a bottom plan view thereof;

FIG. 4 is another side elevational view taken 90 degrees from that shown in FIG. 2;

FIG. 5 is a perspective view taken from the top thereof; and

FIG. 6 is a perspective view taken from the bottom thereof.

I claim:

The ornamental design for an in-line check valve, as shown.
